Des. 228,555
Patented Oct. 9, 1973

228,555

MAIN DISTRIBUTION FRAME-MOUNTED CEN-
TRAL OFFICE SUBSCRIBER CARRIER CHAN-
NEL UNIT SHELF OR SIMILAR ARTICLE

Gene L. Stumpf, Belmont, and Donald G. Tweed, Moun-
tain View, Calif., assignors to GTE Automatic Electric
Laboratories Incorporated, Northlake, Ill.

Filed Oct. 4, 1972, Ser. No. 295,056

Term of patent 14 years

Int. Cl. D14—03

U.S. Cl. D26—14 R

FIG. 2

FIG. 4

FIG. 3

FIG. 5

FIG. 7

FIG. 1 is a front perspective view taken from one side and the top of a main distribution frame-mounted central office subscriber carrier channel unit shelf or similar article showing our new design;

FIG. 2 is a left side view thereof;

FIG. 3 is a top view thereof;

FIG. 4 is a bottom view thereof;

FIG. 5 is a front elevation view thereof;

FIG. 6 is a rear perspective view taken from the other side and the top thereof;

FIG. 7 is a front perspective view taken from the other side and the bottom thereof with the front plate removed therefrom and a channel unit cover and connector mounted therein; and

FIG. 8 is a front perspective view taken from the one side and the top of a main distribution frame-mounted

central office subscriber carrier channel unit shelf or similar article showing an alternate embodiment of our new design.

We claim:

The ornamental design for a main distribution frame-mounted central office subscriber carrier channel unit shelf or similar article, as shown and described.
